UNITED STATES PATENT OFFICE.

GEORGE W. JONES AND FURNEY F. GREEN, OF COMANCHE, TEXAS.

HUB.

SPECIFICATION forming part of Letters Patent No. 351,776, dated November 2, 1886.

Application filed June 9, 1886. Serial No. 204,646. (No model.)

To all whom it may concern:

Be it known that we, GEORGE W. JONES and FURNEY F. GREEN, citizens of the United States, residing at Comanche, in the county 5 of Comanche and State of Texas, have invented a new and useful Improvement in Hubs, of which the following is a specification.

Our invention relates to improvements in 10 hubs for vehicle-wheels; and it consists of the peculiar combination and novel construction and arrangement of the various parts for service, substantially as hereinafter fully set forth, and specifically pointed out in the claims.

15 In the accompanying drawings, Figure 1 is a side elevation of a vehicle-wheel embodying our invention. Fig. 2 is a vertical sectional view taken transversely through the hub and longitudinally of the spokes, only a portion 20 of the latter being shown. Fig. 3 is a longitudinal sectional view through the hub. Fig. 4 is a detached perspective view of one of the radial hub-socket pieces. Fig. 5 is a sectional view through a portion of the fellies to show 25 the means for tightening the tires.

Referring to the drawings, in which like letters of reference denote corresponding parts in all the figures, A designates a hub, B the radial spokes, C the fellies, and D the tire, 30 of a vehicle-wheel which comprises our invention, the peculiar construction of the several parts of which we will now proceed to describe more fully and in detail. The hub A is provided with a central longitudinal opening, a , one end of which is enlarged or flared 35 outwardly to provide an inwardly-projecting flange or ledge, a' , while the other end of the opening of the hub is interiorly threaded, as at a^2 , and in this longitudinal opening is fitted 40 or inserted a metallic bearing or box, E, which is preferably of cast-steel for great durability and strength. One end of the box E, which is in the form of a cylinder or tube, is exteriorly threaded, which screws into the interiorly-threaded end a^2 of the hub, and the opposite end of the tubular box is provided with a projecting rib or flange, e, that takes or bears 45 against the flange or ledge a' of the hub, and prevents further longitudinal movement of 50 the tubular box therein. The outer periphery of the tubular box is provided with re-

cessed key-seats e' , into which are inserted keys E', to secure the box firmly and rigidly in the hub; and the axle of the vehicle bears in this box, which is easily and readily removable from the hub when desired to renew or repair the same, or for any other cause. On its periphery the hub is provided with a circumferential groove or depression, F, the sides of which are curved or inclined, as at f , and the bottom is made quite wide, as at f' , and this groove provides a seat for the radial hub-mortise sections G. These sections G are each cast in a single piece of metal and provided at their middle with projecting tongues, which 60 correspond in size and shape to the peripheral seats of the hub, in which they are snugly and closely fitted, and by means of which they are prevented from having any movement or play laterally of the wheel. These hub-sections 65 are provided with a central socket or opening, g' , in which fits the tenon of the spokes B, and the shoulder on the said spoke formed by cutting the tenon thereon, bears or rests on the segmental or curved edges of the mortise- 70 section of the hub. 75

The side edges of the hub-sections are cut away or reduced to provide an outer flange, j , at each side thereof, and a shoulder or ledge, i , a short distance within the edges of the 80 flange. The hub-mortise sections are segmental in form—that is, they have arc-shaped peripheries and inclined sides, which are tapered toward each other; and when these hub-mortise pieces are fitted on the peripheral 85 seat of the hub they radiate therefrom, and the inclined edges abut against each other, while their curved edges lie concentric with each other to form a complete circle. It will be seen that by this construction the hub-mortise pieces are prevented from outward movement or displacement on the hub, and the peculiarly-formed seat of the latter prevents any play of said sections laterally of the wheel; but to firmly secure the sections to the hub, 90 and permit of their adjustment to keep the wheel in its proper form, we provide a series of threaded pins or studs, H, which pass through the flanges j of the mortise-sections, and have adjusting-nuts J, which bear on opposite sides of the said flange j of the mortise-sections, which flange, it will be observed,

is elevated or held out of contact or engagement with the ends of the hub, so as to provide an intermediate space in which the nut J is fitted. These threaded pins or studs are formed integral with or rigidly secured to the hub, and they are spaced apart thereon and radiate therefrom, and the flange j is provided with an opening through which one of the pins or studs passes.

10. The hub-mortise sections are each provided with two of the pins or studs, which are arranged on opposite sides thereof, and by adjusting the nuts J toward the outer free end of one of the pins or studs on one side of one of the hub-mortise pieces, the end of said mortise on which the nuts bear or act will be forced away from the hub and carry the spokes seated or fitted in the socket in said mortise section with it, while by adjusting the 15 nuts toward the hub the mortise-section and spoke will be drawn inwardly or toward the hub. It will thus be seen that the spokes can be moved toward and from the fellies and the tire to take up or increase the "dish" or 20 cavity in the periphery of the wheel; and the mortise-sections are rigidly and detachably connected to the hub.

Each of the mortise-sections has the inner ends of two spokes fitted therein, and the 25 number of sections employed is proportioned to the number of spokes in the wheel—as, for instance, if the spokes number sixteen, there are four or eight mortise-sections; if eighteen spokes are employed, six sections are used, 30 and so on.

35 Two of the fellies, at diametrically-opposite points in the wheel, are provided with brace-plates K, that are suitably secured thereto, and with protecting-cuffs k, and between the adjoining ends of the fellies are driven keys or wedges L, that are made of either wood or metal, to separate the fellies, and thus tighten the rim of the wheel and the tire thereon.

It will thus be seen that we provide secure 40 and rigid connection or socket for the ends of the spokes, which can be adjusted, and also provide for taking up the slack in the fellies, and the devices are simple and strong in construction, and cheap of manufacture.

45 We are aware that changes in the form and proportion of parts and details of construction may be made without departing from the principle of our invention.

Having thus fully described our invention, 50 what we claim as new, and desire to secure by Letters Patent, is—

1. The combination of a hub having a seat on its periphery, the adjustable sections fitted on the seat of the hub and adapted to receive the spokes, the threaded studs affixed to the hub, 60 and the adjustable nuts fitted on the studs and bearing against the adjustable sections, substantially as described, for the purpose set forth.

2. The combination with a hub provided 65 with a seat on its periphery, and the independently-adjustable sections for the reception of the spokes fitted on the hub and its seat, substantially as described.

3. The combination of a hub having a peripheral seat, the independently-adjustable sections fitted on the hub and the seat thereof, and having their opposing faces inclined or beveled, the threaded studs passing through the sections, and the rotary nuts for adjusting 70 the sections, substantially as described.

4. The combination of a hub having the peripheral seat and the threaded pins, the mortise-sections fitted on the hub, and the nuts for adjustably securing the sections on the pins, 75 substantially as described.

5. The combination of a hub having the peripheral grooved seat, the mortise-sections having the tongue fitted in the seat, the threaded pins or studs passing through the mortise-sections, and the nuts fitted on the pins and bearing against the mortise-sections on opposite sides thereof, substantially as described.

6. The combination of the hub having the peripheral seat, the radial mortise-sections segmental in form and having the tongue fitted 80 on the seat of the hub, the threaded pins, and the nuts, substantially as described.

7. The combination of the hub having the circumferential groove-seat intermediate of 95 its ends, the radial segmental mortise-sections having the central tongue and the reduced edges, the threaded radial pins on the hub and passing through openings in the reduced edges of the mortise-sections, and the nuts I J on the pins and bearing against the mortise-sections, substantially as described.

In testimony that we claim the foregoing as our own we have hereto affixed our signatures in presence of two witnesses.

GEORGE W. JONES.
FURNEY F. GREEN.
